UNITED STATES PATENT OFFICE.

ALVIN MICHAEL, OF NEW YORK, N. Y.

DESIGN FOR BOTTLES.

Specification forming part of Design No. 7,105, dated January 13, 1874; application filed December 19, 1873.
[Term of Patent 14 years.]

To all whom it may concern:

Be it known that I, ALVIN MICHAEL, of New York city, in the State of New York, have invented a Design for Bottles, of which the following is a specification:

The nature of the design is fully represented in the accompanying figures, in which Figure 1 is a side view, and Fig. 2 an edge view.

Similar letters of reference indicate like parts in both the figures.

The neck A is nearly cylindrical, but slightly contracted in diameter in the middle, and of a length forming more than half the height of the entire bottle. The body B is wide and flat, with rounded edges, and a little contracted at the base. The shoulders C C are drooped and rounded. The opposite faces, or nearly flat sides, are inclined, as shown, so that the bottom affords a sufficient base, while the top is of a thickness only a little greater than the diameter of the neck. On one of the faces is molded a distinctive device. It represents an eagle and shield. The device is inclosed in a

ring, and carries over it the words "E Pluribus Unum." The device and motto are familiar on other articles, and need not be minutely described. In the drawing, the eagle is marked D, and the shield E. The inclosing ring is marked G.

I propose to mold the opposite side of the bottle either plain or with the address of the manufacturer.

What I claim as my invention is—

The design for a bottle, herein described, having the cylindrical neck A, wide flat body B, with shoulders C C, drooped and rounded, and with the device of the eagle and shield on one face, the whole forming an ornamental design, as herein set forth.

In testimony whereof I have hereunto set my hand this 6th day of December, 1873, in the presence of two subscribing witnesses.

ALVIN MICHAEL.
